Nat P. Steckler INVENTOR

BY HIS ATTORNEY

Gerry C. Heinricke

UNITED STATES PATENT OFFICE

NAT P. STECKLER, OF NEW YORK, N. Y.

DESIGN FOR A TEETHER

Application filed June 16, 1931. Serial No. 40,225. Term of patent 14 years.

To all whom it may concern:

Be it known that I, NAT P. STECKLER, a citizen of the United States, residing at New York, in the county of New York and State of New York, have invented a new, original, and ornamental Design for Teether, of which the following is a specification, reference being had to the accompanying drawings, forming part thereof.

Fig. 1 is a front elevation of the teether showing my new design, and
Fig. 2 is an edge view thereof.

I claim:

The ornamental design for a teether, as shown.

NAT P. STECKLER.
